Primary Examiner — Melanie H Tung*Assistant Examiner* — Darmawan Truong(74) *Attorney, Agent, or Firm* — Gowling WLG (Canada) LLP(57) **CLAIM**

The ornamental design for a display screen with graphical user interface, as shown and described.

DESCRIPTION

The single FIGURE is a front view of the display screen with graphical user interface showing the new design. The dot-dash line showing of the display screen forms no part of the claimed design. The broken line showing within the display screen of text and portions of the graphical user interface forms no part of the claimed design.
